UNITED STATES PATENT OFFICE.

TIMOTHY LONG, OF CLEVELAND, OHIO.

CAR-UNLOADING APPARATUS.

SPECIFICATION forming part of Letters Patent No. 651,371, dated June 12, 1900.

Application filed May 2, 1895. Serial No. 547,950. (No model.)

To all whom it may concern:

Be it known that I, TIMOTHY LONG, a citizen of the United States, residing at Cleveland, in the county of Cuyahoga and State of Ohio, have invented certain new and useful Improvements in Car-Unloading Apparatus, of which the following is a specification.

My invention relates to improvements in car-dumping machinery whereby the car may be elevated to a suitable point and then turned over sufficiently to allow the load of the car to fall into the chute, by which it is delivered into a receptacle designed to receive it.

The invention consists in the novel features of construction and combination of parts hereinafter described and claimed.

In the drawings, Figure 1 is an end elevation of my improved apparatus. Fig. 2 is a plan view thereof. Fig. 3 is an enlarged detail, partly in section, of one of the car-clamping beams.

A cradle is provided for holding the loaded car. The essential parts of the cradle are the rings B B at the end of the cradle, (and, if desired, one or more intermediate rings B'), the beams C, which connect said rings, and any necessary braces to make the cradle a rigid structure. As shown, the cradle is in the form of a cylinder, open at its ends to permit the car to pass in and out. It is provided with a discharge-spout S for discharging the material dumped into it from the car. The interior of the cylinder is octagonal in form, made so by the beams C', which are secured within the rings B B', a floor c', side walls c², and a top c³, which floor, side, and top are preferably made of sheet metal bolted to the transverse beams C' and longitudinal beams C. The front side wall is extended out beyond the periphery of the cylinder proper and forms a part of the discharge-spout, which under normal conditions stands in a substantially-vertical position. The specific construction of the cradle as shown and described is not important, however, and may be varied at will.

Tracks c⁴ are secured to the floor, and upon them rests the car when in the cradle.

The cradle, with the car in it, is raised and tipped by means of cables connected, arranged, and operated as follows:

D D represent two cables, each of which passes partly around one of the rings B, to which it is secured at a point indicated by F'. Each of these cables passes upward from 55 the rear side of ring B, over sheave G on top of the trestle-tower, and thence down to a winding-drum X, upon which the cable may be wound up. D' D' represent other cables. Each is secured to one of the rings B and 60 passes upward from the front side thereof, over the sheave G' on top of the front side of the trestle-tower, thence over a sheave G² on top of the rear side of said tower and thence to a winding-drum X'. 65

If both sets of cables D D and D' D' are wound up equally and simultaneously, the cradle will be raised without being turned. When it has reached the proper elevation, the winding up of the cable D' is stopped and 70 the winding up of the cables D D is continued, the result being that the cradle is turned over into the position shown by dotted lines in Fig. 1. The contents of the car are dumped through the discharge-spout S 75 into the inclined chute M. This chute is made, preferably, of sheet metal. Its rear end is raised or lowered to the desired level by means of cables U U, which cables are respectively secured to the two rear corners of 80 the chute, from which points they pass upward over the sheaves m m' on top of the trestle-tower and thence down to winding-drums Y. At the front edge of this chute two spouts Q Q are formed. The front edge of the chute is 85 slanted off toward these spouts, and the flange m² is formed upon these slanting edges, whereby the coal or other material is directed to the spouts. A valve Z is pivoted to the chute between the two spouts. This valve may be 90 moved to close the mouth of either spout, and thus direct the material into the other spout. The front end of the chute is raised or lowered to give the chute the desired inclination by means of a cable T, secured to said front edge 95 and extending upward over the sheaves t t' on top of the trestle-tower, and thence down to a winding-drum X².

A tubular spout Q' may be pivoted to the outer end of each spout Q. The outer end of 100 each spout Q' is raised or lowered by means of the cables V, which may be secured on top

of the trestle-tower, from which they pass around a sheave q on the spout Q' , thence over the two sheaves v^2 v^3 on top of the trestle-tower, and then to the winding-drum V' . 5 These spouts Q' are curved down at their outer ends, whereby they properly direct the coal or other material into the holds of vessels or other receptacles provided.

The described construction is of great practical utility in apparatuses which are used for transferring the contents of cars to the holds of vessels, because different vessels stand different distances out of the water, and every vessel settles as the load is put in. The 10 changing of the tide at points where the tide ebbs and flows will also cause a change in the relative position of the vessel and the apparatus; but by the construction described the chute may be placed in any proper position 15 relative to the vessel, and then the cradle need be raised only high enough to dump the contents of the car into the chute.

Weights W may be utilized in assisting in the lifting and tipping of the cradle. Cables 20 N are secured to and wound partly around the rings B and pass up and over the sheaves i , the weights being attached to the free ends of said cables.

The car in the cradle may be held upon the 25 tracks by automatic clamping-bars K , which extend transversely over the car. These bars are tubular, and in each end of each bar is placed a ratchet-block K' , which is movable out of said beam far enough to engage with the vertical rack-bars k^2 , which are secured to the cradle. These ratchet-blocks may be guided between the two plates k , as shown in Fig. 3.

K^3 K^3 represent two bell-crank levers which 30 lie within the beam K and are pivoted thereto. The short vertical end of each lever is connected with one of the ratchet-blocks K' . The long ends of both levers are pivoted loosely to the vertically-movable bar k^4 , which projects upward out of the middle of said beam K , passing through a spring-box k' . In this spring-box is a coil-spring k^3 , which exerts its force to move said bar k^4 downward, which movement transmitted through the levers K^3 35 moves the ratchet-blocks outward. On the upper end of the rod k^4 is an eye k^2 , to which a cable L is attached. This cable passes up over the sheaves l^2 l^3 , and to the free end of this cable a small weight l^3 is attached. These 40 cables L are made of such length that just before the cradle reaches its lowest position these weights l^3 will strike the lower sides of fixed brackets p . Then, as the cradle continues to move down, the pull upon the rod k^4 will first move levers K^3 so as to draw the ratchet-blocks inward, thus releasing the beam K , which beam is prevented from moving down farther with the cradle. It therefore under normal conditions stands above 45 the top of the car, substantially as shown in

Fig. 1. The weight of the beam K is very much greater than the weight of the small weight l^3 . Therefore when the cradle begins its upward movement it moves up to and meets the beam K , and then, as said beam is 50 lifted, the ratchet-blocks are permitted to move outward into engagement with the rack-bars, whereby the car will be held up by said beam when the cradle is turned over.

Having described my invention, I claim— 75

1. In car-dumping machinery, the combination of a car-holding cradle having external rings, and means for holding a car in said cradle, with the cables D D which are secured to and wound partly around said rings and 80 extend upward from one side thereof to overhead sheaves, and thence to winding-drums, and the cables D' D' which are secured to said rings and extend upward from the opposite side thereof to overhead sheaves and 85 thence to independent winding-drums, substantially as and for the purpose specified.

2. In car-dumping machinery, the combination of a car-holding cradle and means for raising it and turning it over, with horizontal beams in the cradle above the car and adapted to engage with the top side thereof, outwardly-movable ratchet-blocks in the ends of said beams, and vertical rack-bars in the 90 cradle with which said ratchet-blocks engage, 95 substantially as and for the purpose specified.

3. In car-dumping machinery, the combination of a car-holding cradle and means for raising it and turning it over, with a horizontal clamping-beam in the cradle above the 100 car, outwardly-movable ratchet-blocks in the ends of said beam, a pair of bell-crank levers for moving said blocks, a spring-actuated rod connected with said levers, a cable secured to said rod and extending upward to an overhead sheave, a weight on its free end, a fixed bracket p , and the vertical rack-bars in the cradle, substantially as and for the purpose specified.

4. In car-unloading machinery, the combination of the car-holding cradle, and means for raising and turning it over, with a plurality of horizontal clamping-beams, ratchet-blocks in the ends of said beams, spring-actuated automatic mechanism for moving said 110 blocks outward when the cradle begins its upward movement, and automatic mechanism for drawing said blocks inward when said cradle reaches its lowest position, and vertical rack-bars in the cradle, substantially as 115 and for the purpose specified.

5. In ear-dumping machinery, the combination of an inclining chute movable bodily up and down whereby it may discharge at the same angle into holds of vessels or other receptacles at different elevations, with means for correspondingly raising a car and dumping its contents into said chute, substantially as and for the purpose specified.

6. In car-dumping machinery, the combi- 130

nation of a chute, cables secured to its rear sides and extending therefrom over overhead sheaves and thence to winding-drums, and a cable secured to its front side and extending therefrom over an overhead sheave and thence to a winding-drum, whereby the height and inclination of said chute may be adjusted, with mechanism for correspondingly raising

a car and dumping its contents into said chute, substantially as and for the purpose to specified.

TIMOTHY LONG.
